UNITED STATES PATENT OFFICE

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

FEEDING MECHANISM FOR OVERSEAMING CUP-FEED MACHINES.

1,137,784.

Specification of Letters Patent.

Patented May 4, 1915.

Application filed April 4, 1911. Serial No. 618,811.

To all whom it may concern:

Be it known that I, LANSING ONDERDONK, a citizen of the United States, residing at New York, in the county of New York, 5 State of New York, have invented certain new and useful Improvements in Feeding Mechanism for Overseaming Cup-Feed Machines, of which the following is a description, reference being had to the accompanying drawing, and to the letters and figures of reference marked thereon.

My invention relates to improvements in overseaming machines, and particularly to those known in the art as cup feed machines, 15 and in its present embodiment is an improvement on the feeding devices of the machine of this character illustrated in my application filed August 4th, 1910, Serial No. 575,589.

20 The object of the present invention is to provide a feed device in which the outer feed member is operated from above, so as to leave an entirely unobstructed space below the engaging point of the two feed 25 cups, whereby the machine is adapted for the sewing of heavy garments, such as sweatshirts and the like, the body thereof being suspended from the feed cups.

30 The invention, therefore, consists in the matters hereinafter described and referred to in the appended claims.

The invention is illustrated in the accompanying drawings, in which,—

35 Figure 1 is a side elevation of a portion of an overseaming machine, showing my feeding mechanism; Fig. 2 is a front view; Fig. 3 is a top plan view; and Fig. 4 a detail sectional view of the outer feed cup and the gears for operating it.

40 In these drawings is shown a portion of the frame 1 of the sewing machine illustrated in my aforesaid application.

In these drawings, 1 represents the inner feed, disk or cup mounted on the upright shaft 2 journaled in a bearing sleeve 3 on the main frame, and engaged at its lower end by the friction grip device 4 and operated in the manner set forth in my aforesaid application. Above its lower end the shaft 2 is provided with a gear wheel 5, which meshes with and drives a gear wheel 6 secured to the lower end of the vertical shaft 7, journaled in bearing lugs 8 on the interior of the frame or casing 9. This shaft 7 extends above the casing and on its

upper end has a belt wheel 10 having projections to engage openings in the belt 11, which is trained around a similar wheel 12 on the upper end of the vertical depending shaft 13. This vertical depending shaft 60 carries on its lower end the gear wheel 14, which through an intermediate gear 15 drives the gear 16 to which the outer feed roll, disk or cup 17 is secured. The outer feed roll, its operating gears and the shaft 13, 65 are carried by a bracket 18, having a web 19 with bifurcated upper portions, the upper portions formed with sleeves 20 embracing the shaft 21 journaled in the ends of a yoke 22, secured to the machine frame. 70

One of the sleeves in the web 19 has a rearwardly extending arm 23 to which is attached a lever 24, operated by a treadle in the usual manner, and controlled by the spring 25. By this arrangement, it will be 75 seen that a positive belt drive is provided for the outer feed roll or disk, that the frame supporting the latter may be swung on its pivotal support by the lever 24 to allow of the insertion and removal of the 80 work, and as the belt is above and the support for the feed roll is a depending one, the space below the feed rolls is unobstructed, so that heavy or bulky garments may be 85 sewed on the machine.

Having thus described my invention, what I claim as new and desire to secure by Letters Patent, is:—

1. In a sewing machine, a feeding mechanism including inner and outer feed rolls or 90 disks, a depending frame pivotally supported above the meeting edges of said rolls or disks and having means for supporting said outer feed roll or disk, and means for positively driving said outer feed roll or disk. 95

2. In a sewing machine, a feeding mechanism including inner and outer feed rolls or disks, a depending frame pivotally supported above the meeting edges of said rolls or disks and having means for supporting said 100 outer feed roll or disk, means for driving said inner feed roll or disk, and means for positively connecting said inner feed roll or disk to the outer feed roll or disk, whereby said feed rolls or disks are operated in 105 unison.

3. In a sewing machine, a feeding mechanism including inner and outer feed rolls or disks, a depending frame pivotally supported above the meeting edges of said rolls or 110

disks and having means for supporting said outer feed roll or disk, means for driving said inner feed roll or disk, means for positively connecting said inner feed roll or disk to the outer feed roll or disk; whereby said feed rolls or disks are operated in unison, said means for connecting the feed rolls or disks including a flexible member located substantially in line with the pivotal support for said frame, whereby the lower end of said frame may be swung outward to separate said feed rolls or disks.

4. In a sewing machine, a main frame, a feeding mechanism including inner and outer feed rolls or disks, a depending pivoted frame supporting the outer feed roll, a shaft carried by said depending frame and geared to the outer feed roll, means for driving the shaft including a shaft on the main frame, means for driving the shaft on the main frame and a horizontal belt extending to said shaft on the main frame, and means for swinging the frame on its pivot.

25 5. In a sewing machine, a feeding mechanism including inner and outer feed rolls or disks, a depending pivoted frame supporting the outer feed roll, a shaft carried by

said depending frame and geared to the feed roll, a belt wheel on the upper end of said shaft, a belt trained thereon, a vertical shaft driven from the inner feed roll and having a belt wheel thereon around which the belt is trained, and means for swinging the frame on its pivot.

6. In a feeding mechanism of the character described including a casing, an inner and outer feed roll or disk, a vertical shaft supporting the inner feed roll or disk, a vertical shaft within the casing driven therefrom, a vertical shaft for driving the outer feed roll or disk, a frame supporting said last mentioned shaft and supporting the outer feed roll, means for pivotally supporting said frame on the casing of the machine, with means for swinging it on its pivot, and a driving connection between the vertical shaft within the casing, and the outer feed roll driving shaft.

In testimony whereof I affix my signature, in presence of two witnesses.

LANSING ONDERDONK.
